UNITED STATES PATENT OFFICE

EDWARD W. CRESSEY, OF BAY CITY, MICHIGAN

JAR OPENER

Application filed July 18, 1931. Serial No. 551,668.

This invention relates to jar openers, and more particularly to an adjustable jar opener, which can be adjusted to facilitate the removal of jar covers of different dimensions, as well as the screw cap or top from ketchup, olive and pickle bottles, in fact any cap or cover which has threaded engagement with a jar, bottle, or other receptacle.

10 Another object is to provide an adjustable jar opener for household use, which is economical to manufacture and assemble, and easy to manipulate.

15 A further object is to provide a jar opener which is readily and easily adjustable, and which can be formed of stampings, permitting mass production at minimum cost.

20 With the above and other objects in view, the present invention consists in the combination and arrangement of parts, herein-after more fully described, illustrated in the accompanying drawing, and particularly pointed out in the appended claims, it being understood that changes may be made in 25 the form, size, proportion, and minor details of construction, without departing from the spirit, or sacrificing any of the advantages of the invention.

30 In the drawing:

35 Fig. 1 is a top plan view of my improved jar opener showing it in position for tightening a screw cap can cover, the dotted lines illustrating the position for removing a cover, and also showing the range of adjustment necessary to accommodate the screw caps on small bottles and receptacles.

40 Fig. 2 is a similar view with the jaw omitted.

Fig. 3 is an edge view.

45 Fig. 4 is a detail side view of the jaw illustrating the washers and rivet assembly.

Fig. 5 is a transverse sectional view taken on the line 5-5 of Fig. 2.

50 Fig. 6 is a similar view taken on the line 6-6 of Fig. 2.

Referring now more particularly to the drawing, the numeral 5 indicates the main body portion of the opener, this is preferably formed of a stamping, the one end having an enlarged opening 6 of a size to per-

mit its being placed over a screw cap jar cover, the opposite end terminating in an elongated handle member 7, so that ample leverage is provided.

A centrally disposed elongated opening 8 is provided in the body portion 5, the edges of said opening being shaped to form racks 9, the notches in said rack being spaced to accommodate the body of a rivet member 10, by means of which the jaw member 11 is secured to the main body, a washer 12 being interposed between the face of the metal and the head of said rivet.

The inner end 13 of the jaw member 11 is turned at right angles to the main body, and the turned edge is crimped or toothed, and when the opener is placed on a cover, and the jaw is shifted to position as indicated in dotted lines in Fig. 1, force is exerted in the direction as indicated by the arrow, this jaw will firmly grip the side wall of the cap or cover so that it can be readily removed, the greater the force exerted on the handle, the tighter the jaw will grip the cover.

75 The main body and jaw are preferably reinforced by turning the edges of the metal, and the washer 12 facilitates the shifting or sliding of the jaw and the main body, the metal of the inner ring portion being ribbed 80 as indicated at 14 so that ample strength is provided.

In practice the opener is placed on a can cover, the jaw is shifted in a direction to suit the size of cover, the rivet 10 traveling 85 between the racks until the jaw engages said cover, the lower end of the jaw is then shifted laterally, until the rivet 10 nests in one of the notches in the rack, to provide an eccentric, the user then grips the end 90 of the handle 6, holding the jar stationary, and rotates the opener to unscrew or tighten the cover, and the leverage, plus the angle of the force exerted will readily unscrew or tighten any cover.

95 It will of course be obvious that the opener may be used for either unscrewing or tightening the covers on jars and bottles, and while in the present instance I have shown the device formed of stampings, it 100

will be understood that castings may be used if desired.

From the foregoing description it will be obvious that I have perfected a very simple, 5 practical, and economical opener for screw cap jar covers and tops.

What I claim is:—

1. A jar opener comprising a main body member including a handle, a centrally disposed opening in said body and adapted to accommodate a jar cover, a slotted opening in the handle directly adjacent said centrally disposed opening and having racks formed on the opposite edges thereof, and 10 a jaw member formed with an arcuate shaped head adjustably mounted on said handle and shiftable forwardly and laterally into engagement with one of the notches in the rack.
2. A jar opener comprising a main body member including a handle, a centrally disposed opening in said body and adapted to accommodate a jar cover, an elongated slotted opening in the handle, the opposite 15 edges being shaped to form spaced apart racks, a jaw mounted on said handle, and provided with an arcuate shaped serrated inner end, a rivet for securing the jaw to the body, said jaw being shiftable forwardly 20 and laterally to permit said rivet nesting in one of the notches in one of the racks.
3. An opener comprising a main body member having a handle formed integral therewith, a centrally disposed opening in 25 said body and adapted to accommodate a cover, a slotted opening in the handle directly adjacent said opening, the opposite edges of said slotted opening being provided with a plurality of spaced apart pockets, a jaw mounted to slide on said body and 30 provided with an arcuate shaped upturned serrated edge adapted to engage a cover, and a rivet for securing said jaw to the body and adapted to nest in one of said 35 pockets when the jaw is in locked position.

In testimony whereof I hereunto affix my signature.

EDWARD W. CRESSEY.
